(57) **CLAIM**

The ornamental design for a display panel or portion thereof with a graphical user interface, as shown and described.

DESCRIPTION

FIG. 1 is a front view of a display panel or portion thereof with a graphical user interface showing a first embodiment of our design; and,

FIG. 2 is a front view of a display panel or portion thereof with a graphical user interface showing a second embodiment thereof.

The outmost broken line rectangle illustrates a display panel or portion thereof that forms no part of the claimed design. The remaining broken lines, including all text, illustrate the graphical user interface or mixed reality environment and form no part of the claimed design.

1 Claim, 2 Drawing Sheets
